UNITED STATES PATENT OFFICE.

JOHN R. HEWETT, OF SCHENECTADY, NEW YORK.

BREACH-MAT.

1,345,771.

Specification of Letters Patent.

Patented July 6, 1920.

Application filed May 27, 1918. Serial No. 236,913.

To all whom it may concern:

Be it known that I, JOHN R. HEWETT, a subject of the King of Great Britain, residing at Schenectady, in the county of Schenectady, State of New York, have invented certain new and useful Improvements in Breach-Mats, of which the following is a specification.

My invention relates to a breach mat for covering holes in the hulls of ships caused by torpedoes, mines, shells, or collisions with other vessels.

The object of my invention is to provide a breach mat which will be sufficiently reinforced to prevent its being forced into the hole by the enormous pressure of water, and which, although normally stowed compactly away, may be readily moved to the portion of the ship where the hole has been made and quickly placed in position over the hole without difficulty or interference by the inrushing water. My breach mat is so arranged that it may be readily tied to the side of a vessel, so that even if the pressure on both sides of the mat is balanced, it will remain in its proper position.

The various features of novelty which characterize my invention are pointed out with particularity in the claims annexed to and forming a part of this specification. For a better understanding of my invention reference may be had to the following description taken in connection with the accompanying drawing, in which Figure 1 is an elevation of my breach mat in its rolled or folded up position; Fig. 2 is a rear view of the mat, with parts removed and other parts partially unfolded; Figs. 3 and 4 are views similar to Fig. 1 with parts further unfolded, Fig. 3 having certain parts broken away; Fig. 5 shows the mat completely unfolded; Fig. 6 is a section of a ship with mat applied thereto; Fig. 7 is a view partly in section of a detail; Fig. 8 is a bottom view of the detail of Fig. 7; and Fig. 9 is a view of another detail.

Referring to the drawings, my breach mat comprises beams 1 which are normally held in a horizontal position but may be released so as to move into a vertical position and a sheet member 2 which is normally folded or rolled up but may be unrolled over the beams 1. The beams 1 are pivoted to a member 3 which also supports the sheet member 2. The sheet member 2 is made of

canvas, tarpaulin or the like and is provided with horizontal reinforcing members 4.

Referring more in detail to the construction illustrated, the member 3 is shown as forming part of a carriage 37, mounted for movement along the side of a vessel by means of wheels 6 which run on rails 7 mounted on the side of the vessel. Since the beams 1 and the sheet member 2 are both supported on this member, and the member 3 is connected to the carriage 37 by links 38, the whole operative part of my mat is pivotally mounted about the rail 7 and when unfolded can swing about this rail as its axis.

The beams 1 are shown as being arranged in groups, the beams in each group being linked together by flexible links 8. The beams of adjacent groups when folded up extend in opposite directions from their pivots as clearly shown in dotted lines in Fig. 2. They are held in their folded-up position by means of catches 9 which are released by members 10 operated by a rope 11 and windlass 12, the members 10 are pressed forward into the latched position by springs 13. In order to ease the motion of the beams after they are released, cables 14, having one of their ends attached to each of the groups 85 of beams and the other end attached to a retarding device such as one member of a dash-pot 15, are provided. A rope or cable 16 is provided for tying the groups of beams together after they have been moved into a vertical position. This rope or cable is operated by means of the windlass 17. The cable goes down through a pipe 18 in the innermost beam of one of the groups of beams to the lower end thereof and then up this same beam through collapsible links or a collapsible tube 19, then across to the adjacent beam of the other group down through a collapsible link or collapsible tube in this beam and is fastened to the end of 100 this latter beam. This construction is most clearly shown in Figs. 2, 7 and 8. By this arrangement the cable 16 is continually maintained under tension as it moves to tie the groups of beams together. The sheet 105 member 2 is supported from the member 3 by means of links 20 and is held in its rolled up position by means of ropes or cables 21, one end of each of which is fastened to the member 3 and the other end 110

is wound around each of windlasses 22. The windlasses 22 are actuated by a shaft 23, gearing 24 and a shaft 25. The sheet member 2 is unrolled by means of ropes or cables 26 and a windlass 27, as will be explained more fully hereinafter. The sheet member may be tied to the beams 1 by means of the ropes or cables 26. These ropes or cables 26 have one end tied to the sheet member 2, and when the mat is rolled up, goes around the sheet member, then down through collapsible links or collapsible tubes in certain of the beams. These ropes are illustrated in the drawing as going down the outer beams of the groups, then up these same beams through a pipe and then about the windlass 27. The construction of these outer beams is similar to that described above in connection with the path of the rope 16 and as illustrated in Figs. 7 and 8. By this arrangement the ropes or cables 26 are continually maintained under tension as they move to unroll the sheet member and to tie it to the beams. The sheet member, when completely unrolled, extends below the ends of the beams 1 and may be fastened to the side of the vessel by means of chains 28 going completely about the hull. These chains are attached to the sheet member by means of ropes or cables 29. The ropes or cables 29 may be fastened to the mat by means of collapsible links 30 so that when the sheet member is rolled up, these cables will be so supported that they will not become entangled with any part of the mat. The reinforcing members 4 are suitably fastened in the sheet member 2 and extend throughout the length of the mat. I have illustrated one such member 4 in full and the adjacent one in dotted lines in Fig. 3. The end portions of the sheet member are constructed so that they bend inwardly toward the side of the vessel as the mat unrolls. I have illustrated one way of accomplishing this, which consists in making each of the reinforcing members 4 in a number of sections, the end sections being joined together by spring hinges 31 which force the end section of the reinforcing members 4 and consequently the end portions of the sheet member inwardly toward the side of the vessel.

Each of the windlasses 12, 17 and 27 and the shaft 25 may be operated by an electric motor 32 through a shaft and gearing as shown in Fig. 9, each of the windlasses 12 and 17 and the shaft 25 being provided with a clutch for connecting them to the shafting when it is desired to turn the same. The windlasses 12, 17 and 27, the electric motor 32 and the shafts 23 and 25 are mounted on the carriage 37. The mat, as a whole, may be moved along the rails 7 by an electric motor (not shown) as is usual in cranes and the like, and may be held in any desired position by a suitable brake as

ordinarily provided on such cranes. The mat may be stowed in position on the side of the vessel and held against movement by chains about the same. These chains have been omitted from the drawings for the sake of clearness. When the mat is stowed away, it also can be covered by tarpaulin. These chains and the tarpaulin can be readily dropped from around the mat by a suitable releasing device when it is desired to put the mat in operation.

The operation of my breach mat is as follows: When a hole is torn in the side of a vessel due to a collision, mine, torpedo, or the like, the chains and the covering holding the same against the side of the ship are dropped from around the breach mat and the same is then moved along the rails 7 in its folded-up condition to a position directly over the place where the hole has been made. The windlass 12 is clutched to the shaft driven by the motor 32 and thus turned to move the members 10 and thereby release the catches 9, thus releasing the groups of beams so that they assume a position somewhat like that shown in Fig. 2. As soon as the catches 9 are released the windlass 12 is unclutched from the motor. The windlass 17 is then clutched to the shaft driven by the motor and thereby rotated so as to pull on the rope 16. As the windlass 17 is turned, the rope will move out of the collapsible tube 19, under tension, as shown in Fig. 2, tending to bring the beams together into a vertical position and finally tying them together as illustrated in Fig. 3, whereupon the windlass 17 is unclutched and braked. The shaft 25 is then connected to the motor 32 through the gearing and its clutch so as to rotate the shaft 23 through the gearing 24 and thus turn the windlass 27 in one direction and the windlasses 22 in the opposite direction to lower the sheet member 2. As the windlass 27 turns, it pulls on the ropes 26 to unroll the sheet member, the ropes 21 being slackened at the same time. In this way, the sheet member is kept continually under control as it is unrolled, that is, it cannot unroll any faster than the ropes 21 permit it to unroll, and the portions of the ropes 21 that are paid out depend on the portions of the ropes 26 that are pulled in. As the ropes 26 are wound up to lower the sheet member, these ropes are pulled out of the collapsible tubes or links in the beams. Figs. 3 and 4 show the sheet member as it is being lowered, and Fig. 5 shows it completely lowered. When it reaches this position, the ropes 26 fasten the sheet member to the beam 1, whereupon the shaft 25 is stopped and braked, thus stopping and braking the windlasses 22 and 27. In order to tie the mat, as a whole, to the side of the vessel, chains 28 are put around the hull of the vessel connected to 130

the cables 29 and then the chains 28 are pulled in so that the cables 29 break the collapsible links 30 and finally firmly fasten the mat to the side of the vessel with the 5 lower section of the sheet member extending to the bottom thereof as illustrated in Fig. 6. The mat now completely covers the hole, and the water which has rushed into the vessel may be pumped up.

10 It will be noted that my construction of breach mat is such that it cannot be forced into the hole by the inrushing water and that the sheet member unfolds without being interfered with by the pressure of the water 15 rushing into the hole. If the pressure on both sides of the mat is balanced, that is, if the compartment in which a hole has been made is filled with water, it is preferable to immediately tie the beams 1 to the 20 side of the vessel by means of chains or ropes engaging the ends of the beams and going around the hull of the vessel, in a way similar to that of the ropes 29 and the chains 28.

25 I desire it to be understood that I aim in the appended claims to cover all modifications which do not depart from the spirit and scope of my invention.

What I claim as new and desire to secure 30 by Letters Patent of the United States, is:—

1. A breach mat comprising a plurality of beams normally held in a horizontal position, a sheet member normally rolled up, means for releasing said beams so that they 35 may move into a vertical position, and means for releasing said sheet member so that it may unroll over said beams.

2. A breach mat comprising a plurality of beams normally held in a horizontal position, a sheet member normally rolled up, means for releasing said beams so that they 40 may move into a vertical position, means for releasing said sheet member so that it may unroll over said beams, and means for tying said sheet member to said beams after said sheet member has been unrolled.

3. A breach mat comprising a plurality of beams normally held in a horizontal position, a sheet member normally rolled up 45 and provided with horizontal reinforcing members, means for releasing said beams so that they may move into a vertical position, and means for releasing said sheet member so that it may unroll over said beams.

55 4. A breach mat comprising a plurality of beams normally held in a horizontal position, a sheet member normally rolled up and provided with horizontal reinforcing members, means for releasing said beams so that 60 they may move into a vertical position, means for releasing said sheet member so that it may unroll over said beams, and means for tying said sheet member to said beams after said sheet member has been unrolled.

5. A breach mat comprising a plurality of beams normally held in a horizontal position, a sheet member normally rolled up, means for releasing said beams so that they may move into a vertical position, means for 70 releasing said sheet member so that it may unroll over said beams, and means for tying said sheet member to said beams after said sheet member has been unrolled, said tying means being continually under tension as said sheet member is tied to said beams.

6. A breach mat comprising a plurality of beams normally held in a horizontal position, a sheet member normally rolled up 80 and provided with horizontal reinforcing members, means for releasing said beams so that they may move into a vertical position, means for releasing said sheet member so that it may unroll over said beams, and 85 means for tying said sheet member to said beams after said sheet member has been unrolled, said tying means being continually under tension as said sheet member is tied to said beams.

7. A breach mat comprising a member, a plurality of beams pivoted to said member and normally held in a horizontal position, a sheet member supported by said first-mentioned member and normally rolled up, 95 means for releasing said beams so that they may move into a vertical position and means for releasing said sheet member so that it may unroll over said beams.

8. A breach mat comprising a member, a 100 plurality of beams pivoted to said member and normally held in a horizontal position, a sheet member supported by said first-mentioned member and normally rolled up, means for releasing said beams so that they 105 may move into a vertical position, and means for releasing said sheet member so that it may unroll over said beams, and means for tying said sheet member to said beams after said sheet member has been unrolled.

9. A breach mat comprising a member, a plurality of beams pivoted to said member and normally held in a horizontal position, a sheet member supported by said first-mentioned member and normally rolled up, 115 means for releasing said beams so that they may move into a vertical position, means for releasing said sheet member so that it may unroll over said beams, and means for tying said sheet member to said beams after 120 said sheet member has been unfolded, said tying means being continually under tension as said sheet member is tied to said beams.

10. A breach mat comprising a member, a plurality of beams pivoted to said member and normally held in a horizontal position, a sheet member supported by said first-mentioned member, normally rolled up and provided with horizontal reinforcing members, means for releasing said beams so that 130

they may move to a vertical position, and means for releasing said sheet member so that it may unroll over said beams.

11. A breach mat comprising a member, a plurality of beams pivoted to said member and normally held in a horizontal position, a sheet member supported by said first-mentioned member, normally rolled up and provided with horizontal reinforcing members, means for releasing said beams so that they may move to a vertical position, means for releasing said sheet member so that it may unroll over said beams, means for tying said sheet member to said beams after said sheet member has been unrolled.

12. A breach mat comprising a member, a plurality of beams pivoted to said member and normally held in a horizontal position, a sheet member supported by said first-mentioned member, normally rolled up and provided with horizontal reinforcing members, means for releasing said beams so that they may move to a vertical position, means for releasing said sheet member so that it may unroll over said beams, and means for tying said sheet member to said beams after said sheet member has been unrolled, said tying means being under tension as said sheet member is tied to said beams.

13. A breach mat comprising a member, a plurality of beams pivoted to said member and arranged in groups, said beams in each group being linked together, each group of beams being normally held in a horizontal position, the beams of adjacent groups extending in opposite directions from their pivots, a sheet member supported by said first-mentioned member and normally rolled up, means for releasing said beams so that they may move into a vertical position, means engaging adjacent groups of beams for tying said groups of beams together in the vertical position and means for releasing said sheet member so that it may unroll over said beams.

14. A breach mat comprising a member, a plurality of beams pivoted to said member and arranged in groups, said beams in each group being linked together, each group of beams being normally held in a horizontal position, the beams of adjacent groups extending in opposite directions from their pivots, a sheet member supported by said first-mentioned member and normally rolled up, means for releasing said beams so that they may move into a vertical position, means engaging adjacent groups of beams for tying said groups of beams together in the vertical position, means for releasing said sheet member, so that it may unroll over said beams, and means for tying said sheet member to said beams after said sheet member has been unrolled.

15. A breach mat comprising a member, a plurality of beams pivoted to said member

and arranged in groups, said beams in each group being linked together, each group of beams being normally held in a horizontal position, the beams of adjacent groups extending in opposite directions from their pivots, a sheet member supported by said first-mentioned member, normally rolled up and provided with horizontal reinforcing members, means for releasing said beams so that they may move into a vertical position, means engaging adjacent groups of beams for tying said groups of beams together in a vertical position, and means for releasing said sheet member so that it may uproll over said beams.

16. A breach mat comprising a member, a plurality of beams pivoted to said member and arranged in groups, said beams in each group being linked together, each group of beams being normally held in a horizontal position, the beams of adjacent groups extending in opposite directions from their pivots, a sheet member supported by said first-mentioned member, normally rolled up and provided with horizontal reinforcing members, means for releasing said beams so that they may move into a vertical position, means engaging adjacent groups of beams for tying said groups of beams together in the vertical position, means for releasing said sheet member so that it may unroll over said beam, and means for tying said sheet member to said beams after said sheet member has been unrolled.

17. A breach mat comprising a member, a plurality of beams pivoted to said member and arranged in groups, said beams in each group being linked together, each group of beams being normally held in a horizontal position, the beams of adjacent groups extending in opposite directions from their pivots, a sheet member supported by said first-mentioned member, normally rolled up and provided with horizontal reinforcing members, means for releasing said beams so that they may move into a vertical position, means engaging adjacent groups of beams for tying said beams together in the vertical position, said last-mentioned means being under tension as it moves to tie said groups of beams together, means for releasing said sheet member so that it may unroll over said beams, and means for tying said sheet member to said beams.

18. A breach mat comprising a member, a plurality of beams pivoted to said member and arranged in groups, said beams in each group being linked together, each group of beams being normally held in a horizontal position, the beams of adjacent groups extending in opposite directions from their pivots, a sheet member supported by said first-mentioned member, normally rolled up and provided with horizontal reinforcing members, means for releasing said

- tical position, said last-mentioned means being under tension as it moves to tie said groups of beams together, means for releasing said sheet member so that it may unroll over said beams, and means for tying said sheet member to said beams after said sheet member has been unrolled, said tying means being under tension as said sheet member is tied to said beams.
- 10 26. The combination with a vessel, of a breach mat comprising a member mounted for movement along the side of said vessel, a plurality of beams pivoted to said member and arranged in groups, said beams in each 15 group being linked together, each group of beams being normally held in a horizontal position, the beams of adjacent groups extending in opposite directions from their pivots, a sheet member supported by said 20 first-mentioned member, normally rolled up

and provided with horizontal reinforcing members, means for releasing said beams so that they may move into a vertical position, means engaging adjacent groups of beams for tying said beams together in the vertical position, said last-mentioned means being under tension as it moves to tie said groups of beams together, means for releasing said sheet member so that it may unroll over said beams, means for tying said sheet member to said beams after said sheet member has been unrolled, said tying means being under tension as said sheet member is tied to said beams, said sheet member extending below the ends of said beams, and means for tying 35 said mat to the side of said vessel.

In witness whereof, I have hereunto set my hand this 24th day of May, 1918.

JOHN R. HEWETT.
